UNITED STATES PATENT OFFICE.

JOHN M. MARIS, OF PHILADELPHIA, PENNSYLVANIA.

DESIGN FOR DRAWER-PULL.

Specification forming part of Design No. 5,762, dated April 9, 1972.

Specification describing a Design for a Drawer-Pull, invented by JOHN M. MARIS, of the city and county of Philadelphia, State of Pennsylvania.

In the accompanying drawing, Figure 1 is a front view; Fig. 2, an end view; and Fig. 3, an inverted plan view of a drawer-pull made in accordance with my design.

The drawer-pull is plain and flat at the back, as shown at *a*, Figs. 2 and 3, has an inclined front, *b*, and is formed with a screw-hole, *d*, at each end. The top and bottom *e* and *f* of the drawer-pull are formed on curved lines, as shown, and the ends *g* are partly straight and partly curved, and are rounded at the bottom into two scroll-like projections, *h h*, which are curved outward and inward, and rounded into the curved bottom *f* of the body of the drawer-pull, in the manner plainly shown in the drawing, so as to form convenient handles, beneath

which the fingers can be inserted in opening or closing the drawer to which the pull is attached. In the inclined front *b* of the pull is a curved opening, *k*, through which can be exposed to view a label or placard contained within a recess formed for its reception at the back of the pull.

I claim—

1. The design for the scroll-like projections *h h*, substantially as shown and described.
2. The design for the whole drawer-pull, substantially as described, and as illustrated in and by the accompanying drawing.

In testimony whereof I have signed my name to this specification in the presence of two subscribing witnesses.

JOHN M. MARIS.
